UNITED STATES PATENT OFFICE.

HARRY SAMUEL BICKERTON BRINDLEY, OF WESTMINSTER, LONDON, ENGLAND,
ASSIGNOR TO BOILER SCALERS LIMITED, OF WESTMINSTER, LONDON, ENGLAND.

FLUE-SCRAPER.

1,116,982.

Specification of Letters Patent. Patented Nov. 10, 1914.

Application filed February 17, 1913. Serial No. 748,985.

To all whom it may concern:

Be it known that I, HARRY SAMUEL BICKERTON BRINDLEY, a subject of the King of Great Britain and Ireland, and residing at 5 Queen Anne's Chambers, Westminster, London, S. W., England, have invented certain new and useful Improvements in Flue-Scrapers, of which the following is a specification.

- 10 This invention relates to improvements in connection with apparatus to be used for cleaning and scaling tubes, conduits and the like and has more particular reference to that class of apparatus in which a number 15 of cutters are adapted to be driven against the scale or other material to be removed from the pipe or the like by means of blows from a pneumatic or other hammer or like device.
- 20 The object of the present invention is to produce a device of the above nature capable of performing its functions in an efficient manner while at the same time being extremely flexible and especially adaptable for 25 dealing with curved or irregular tubes.

The invention consists in tube cleaning or like apparatus comprising a cutter or cutters, means for operating the cutters and resilient means for retaining the cutters 30 pressed against the surface of the tube or the like to be scaled.

The invention also consists in tube-scaling or like apparatus as above referred to in which a spring-pressed ferrule having inclined faces adapted to engage similar faces 35 upon the cutter or cutters is employed as the resilient means for retaining the cutters in their position.

The invention also consists in other devices 40 thereafter more particularly referred to.

The accompanying drawings illustrate two modes of carrying out the invention.

Figure 1 is a longitudinal sectional elevation showing one convenient form of tube-cleaning apparatus constructed in accordance with the invention. Fig. 2 illustrates a modification and its mode of operation when cleaning a curved or irregular tube.

In carrying my invention into effect in 50 one convenient manner when constructing apparatus for cleaning or scaling boiler tubes I arrange a cutter composed of a number of cutting elements *a* having each one or

more cutting edges as desired within the outer end of the barrel or cylinder *b* of the 55 pneumatic hammer or within an extension thereof and to the cylinder *b* I attach by screwing or otherwise a central rod or shaft *c*, the piston *d* of the pneumatic hammer being adapted to surround the shaft and being operated in any usual or desired manner. The cutters *a* are held in their outermost position, that is, so that they press against the walls of the tube or the like to be cleaned by means of an expander *e* held 60 in place by a suitable spring *f*, the latter in turn being securely retained in position by means of a cap *g* screwed or otherwise secured to the end of the rod or shaft *c* and provided with any convenient restraining 70 device as the spring washer *h* for the purpose of holding the cap firmly in position. The expander *e* and cutters *a* are formed with inclined engaging faces *i* so that under the action of the spring *f* the expander 75 forces the cutter outward while it will be seen that the arrangement as a whole is extremely flexible and particularly suited for dealing with curved or irregular tubes, the inner ends of the expander and the cutting 80 elements being preferably rounded as shown to increase the flexibility. Further, the expander is itself preferably formed with a corrugated or other suitable face *m* so that it may act when desired as an auxiliary cutting element particularly suitable for dealing with thick scale.

Fig. 2 illustrates a slightly modified form of apparatus and shows its mode of operation when dealing with a curved or irregular 85 tube.

If desired, in any modification of my invention I provide a plurality of serrations *k* in such a manner as to form cutting faces upon the cutter surfaces of the cutters *a*, 95 the grooves preferably commencing just below the circumferential cutting edge or edges so as not to injure the tubes and being particularly advantageous for dealing with thin scale. The cutting edges themselves 100 are spaced some little distance apart from one another.

By reason of my method of anchoring the cutters by means of the central rod *c* the cutters are free to rotate about the stalk and 105 in practice do rotate in this manner, thus

obviating the necessity for the turning of the tool by the operator during the scaling operation.

It will be obvious that I may suitably modify the form of cutters and the construction of the devices when dealing with flat surfaces and I do not wish to confine myself to any particular constructional details hereinbefore given by way of example 10 nor to any particular application described, and I may modify the form of cutting elements to suit any particular practical requirements.

Having now described my invention, what 15 I claim as new and desire to secure by Letters Patent is:—

1. In a tube cleaning apparatus; a cylinder; an expansible cutter carried by one end of the cylinder; a rod extending through 20 the cylinder and through the cutter; an expander slidably upon the rod and into engagement with the cutter; means to hold the expander yieldingly in engagement with

the cutter; and a piston mounted to reciprocate within the cylinder and slidable upon 25 the rod into engagement with the cutter.

2. In a tube cleaning apparatus; a cylinder; an expansible cutter carried by one end of the cylinder; a rod extending axially through the cylinder and through the cutter; an expander mounted slidably upon the 30 rod; a spring adapted to hold the expander yieldingly in engagement with the cutter; an adjusting nut adapted to vary the tension on the spring; and a piston mounted 35 within the cylinder and slidable upon the rod into engagement with the end of the cutter opposite its engagement with the expander.

In testimony whereof I have signed my 40 name to this specification in the presence of two subscribing witnesses.

HARRY SAMUEL BICKERTON BRINDLEY.
